UNITED STATES PATENT OFFICE.

NILS A. WAHLBERG, OF WILKINSBURG, PENNSYLVANIA, ASSIGNOR TO WESTINGHOUSE ELECTRIC & MANUFACTURING COMPANY, A CORPORATION OF PENNSYLVANIA.

INSULATOR CONNECTER.

Application filed August 12, 1922. Serial No. 581,312.

My invention relates to connecting means and particularly to connecting means for suspension insulators.

One object of my invention is to provide a device of the above-indicated character that shall be simple and durable in construction, economical to manufacture and effective in its operation.

Another object of my invention is to provide a metallic envelope or cover for an insulator connector that shall compensate for electrostatic-field-disturbing factors caused by the form of the mechanical connecting parts.

15 A further object of my invention is to provide a connector that shall greatly facilitate the operations of connecting, disconnecting and replacing the units of series-string suspension insulators.

20 Heretofore, many devices such as arcing rings, arcing horns and field-distributing members have been employed to improve the operation of high-potential insulators.

25 Irregularly shaped parts disposed in the electrostatic field at positions of high-potential gradient tend to concentrate the field and to cause failure at voltages below that which the insulator might otherwise withstand.

30 Parts having important mechanical functions are frequently disturbing elements because it is not always feasible to construct them for mechanical efficiency and, at the same time, to have them of symmetrical contours relative to the electrostatic field.

35 It is my aim to provide a connector that shall be satisfactory from a mechanical standpoint and that shall offer no considerable disturbing influence in the electrostatic field of an insulator.

40 In practicing my invention, I provide a connector that shall permit the mechanical considerations to be taken care of in a simple and effective manner and that shall cause no undue disturbing influence in the electrostatic field. In other words, the connector may be variously constructed in accordance with the exact mechanical requirements as to strength and size and, at the same time, be shaped to uniformly distribute the electrostatic field.

45 Figure 1 of the accompanying drawings is a longitudinal side view, partially in elevation and partially in section, of a series-

55 string suspension insulator employing the connector of my invention;

Fig. 2 is a detail plan view of a member of the connector, and

Fig. 3 is a side elevational view of the member shown in Fig. 2.

60 A series-string suspension insulator of one type, with which the connector of my invention may be employed, may comprise a plurality of insulating members 1, of well-known construction, having recessed head portions 2 for the reception thereover of metal cap members 3 and for the reception therein of pin members 4.

65 The cap members 3 and the pin members 4 are provided with clevis portions 5 and eye-70 portions 6, respectively, for the reception of a pin 7.

75 Under ordinary conditions, the eye-and-clevis structure, while very satisfactory from a mechanical standpoint, offers considerable disturbance to the electrostatic field between the members 1 by reason of the relatively sharp edges of the parts and the projecting portions thereof. The field concentrates on these edges and projections and causes breakdown or flash-over at relatively low-voltage values.

80 To permit the use of an eye-and-clevis structure of any desired mechanical strength, I provide a cap or cup member 8, preferably 85 of relatively thin pressed metal, which is symmetrically formed to uniformly distribute the electrostatic field and which constitutes a substantially totally enclosing envelope for the connector.

85 The member 8 is provided with an opening 9 by which it may surround the pin 4 and be moved to and from a position over the eye and clevis along the longitudinal axis of the insulator. Indentations or inwardly projecting portions 10 are also provided on the member 8 to frictionally engage the ends of the member 7 to thereby hold both the pin 7 and the member 8 in position.

90 In assembling the units, the member 8 is placed in position over the end of the pin 4 and moved inwardly therealong to permit the eye-and-clevis portions and the pin 7 to be placed in position. The member 8 is 95 then withdrawn along the pin 4 to the position shown in the drawings.

100 In addition to uniformly distributing elec-

trostatic field stresses adjacent to the eye-and-clevis connector, the member 8 obviates the necessity of a cotter pin or other small unhandy parts for holding the pin in place and facilitates the manipulation of the insulator parts to a high degree.

While I have shown and described a particular form of my invention, changes may be effected therein without departing from 10 the spirit and scope thereof as set forth in the appended claims.

I claim as my invention:

1. The combination with a high-voltage device including a pair of cooperating connector members and a holding pin therefor, of an electrostatic-stress-distributing member of substantially cup-shape surrounding the adjacent connected portions for holding the pin in position, said member of cup-shape having a rounded portion joining its side and end walls and an opening in its end wall by which it surrounds one of said first members and is permitted longitudinal movement relative thereto.
2. The combination with an insulator having a connector portion, a cooperating member having a shank portion and a portion for connection to said first connector portion and an element for holding said portions together, of an electrostatic-stress-distributing member of substantially cup-shape for surrounding the adjacent connector portions and said element for holding the same together and having an opening in its bottom wall by which it surrounds said shank and is permitted longitudinal movement thereon, the side and end walls of said cup being joined by a portion of rounded contour.
3. The combination with an insulator of the cap-and-pin type having a connector portion on the cap, a cooperating member embodying a shank and a portion for connection to said cap-connector portion and an element for holding said portions together, of an electrostatic-stress-distributing member of substantially cup-shape movably mounted on said shank and normally adapted to rest in position over said con-

necter portions and said element to hold the 50 same together, the open-end perimeter of said cup being shaped to fit against the insulator cap.

4. In a suspension-insulator device, the combination with cap-and-pin terminal members, eye and clevis elements, one of which constitutes a portion of a cap and another of which constitutes a portion of a pin of said device, and a connector pin for said elements, of means for preventing the 60 concentration of electrostatic stresses on said elements and connector pin and holding the same together comprising a metal member of substantially cup-shape having an opening 65 in its end wall for mounting the same around said terminal pin in longitudinally movable relation thereto, said cup member having a rounded perimeter between its side and end walls and being for operative positioning over said eye and clevis portions 70 with its open end closely fitting a portion of said cap terminal member.

5. In a suspension-insulator device, the combination with cap-and-pin terminal members, eye and clevis elements, one of 75 which constitutes a portion of a cap and another of which constitutes a portion of a pin of said device, and a connector pin for said elements, of means for preventing the concentration of electrostatic stresses on said 80 elements and connector pin and holding the same together comprising a metal member of substantially cup-shape having an opening in its end wall for mounting the same around said terminal pin in longitudinally 85 movable relation thereto and inner-side-wall portions for engagement with the ends of said connector pin, said cup member having a rounded perimeter between its side and end walls and being for operative positioning 90 over said eye and clevis portions with its open end closely fitting a portion of said cap terminal member.

In testimony whereof, I have hereunto subscribed my name this 5th day of August 95 1922.

NILS A. WAHLBERG.
